SOUND GENERATOR

Arthur H. Brooks, Cambridge, Mass., assignor to the United States of America as represented by the Secretary of the Navy

Application September 14, 1945, Serial No. 616,388

11 Claims. (Cl. 116—27)

This invention relates to a sound generator and is illustrated herein as embodied in an underwater noise-making device adapted for use as a countermeasure against acoustically detonated explosive instruments, or the detection of a ship using the device by another ship having underwater sound locating equipment.

Torpedoes and mines of the so called "acoustic" type have been designed to utilize the noise of a ship's machinery or screw action to actuate their detonating devices. Moreover, owing to the effectiveness of water as a sound conducting medium, the position of one ship from another having underwater sound locating equipment can be determined by the use of either listening or echo-ranging apparatus which is commonly embodied in such equipment.

Noise making devices have commonly been mounted in ships as countermeasures for detonating mines but such devices have an effective angular scope of limited extent and are usually directed forwardly of the ship only. Furthermore, any ship carrying an operating noise-maker is obviously a better target for the same reason.

In view of the foregoing, it is a principal object of the invention to provide an improved sound generator for confusing the enemy when the ship having the device is under detection, and for affording an effective countermeasure against acoustic torpedoes which may approach the ship from any direction, as well as against a listening or echo ranging operation directed at the ship.

To this end, the invention provides a portable and expendable sound generator adapted to be dropped over the side of a ship from any part thereof and to produce sound or noise of such intensity as to mask that of the ship, and any echo ranging sound impulses, the sound being propagated substantially uniformly in all directions. Accordingly, sound from the generator will detonate any torpedo that would be detonated by the noise of the ship before the torpedo comes dangerously close to the ship. Similarly, any echo ranging impulse reflected by the ship will be obscured in the noise from the generator.

As another feature of the invention, the sound generator has associated therewith a float, from which the generator is suspended at a desirable level below the surface of the water until the generator becomes exhausted. During the period of its operation, the generator has a substantially fixed position with respect to which a ship under detection can maneuver in any suitable direction to take advantage of the masking or shielding effect of the generator, or the doubt created on the enemy ship as to which source of noise is the real target.

In order to avoid disclosing the position of the ship using the generator, the float is constructed and arranged slowly to lose its buoyancy so that by the time the sound from the generator ceases the float and generator will have started to sink to the bottom.

With these and other objects and features in view, the invention will now be described with reference to the accompanying drawings which illustrate a preferred em-

2

bodiment of the invention and will be pointed out in the claims.

Fig. 1 is a side elevation of a sound generator embodying the invention, the float or container for the generator being shown in section.

Fig. 2 is a plan view of the left-hand part of the generator shown in Fig. 1.

Fig. 3 is a fragmentary elevation of the time-delay trigger mechanism for actuating the supply valve.

Fig. 3A is a fragmentary sectional view taken along the line 3A—3A of Fig. 3 further illustrating the arrangement of the trigger mechanism for actuating the supply valve, and

Fig. 4 is a view in elevation showing the sound generator suspended in the water by the float.

The illustrated sound generator comprises a float or container 10 which is adapted to house a sound generator unit 12, the float and unit being connected by a coiled line 14 about twenty-five feet in length. The unit 12 comprises a resonator tank 16 having therein a supply of gas under high pressure. Many kinds of gas can be used satisfactorily, but CO₂ is especially suitable since it can be liquified readily, and is available in many places. The gas is delivered to an automatic gas operated hammer 18, the striker 20 of which impinges rapidly upon an anvil 22 fixed to the resonator tank. The hammer 18 may be of the conventional hand riveting type which has a striking frequency of about 90 blows per second and which operates at a pressure of approximately 90 pounds per square inch.

When the sound generator is to be used, the unit 12 is removed from the float through an opening in its lower end which is normally closed by a hinged door 24 when the generator is stowed. The float 10 and unit 12 are then dropped off the ship, whereupon the unit 12 sinks, pulls the line 14 taut, and causes the float to stand vertically in the water as illustrated in Fig. 4. This action of the unit 12 and float 10 occurs so rapidly as to trap within the float practically all of the air which it contained when dropped overboard. The upper end of the float 10 is closed except for a small orifice 26 which allows air to escape from float 10 slowly enough as to destroy the buoyancy of the float as soon as the gas in the resonator tank 16 has become exhausted.

The resonator tank 16 is composed of a cylindrical body having hemispherical ends, the wall thickness of which is great enough to withstand pressure in the neighborhood of 2,000 p.s.i. The illustrated resonator tank has windings of piano wire 28 soldered thereto which are intended to avoid any shrapnel effect which might result from the tank's bursting if hit by a projectile. Fixed to the discharge end of the tank 16 is a bracket 30 on which the hammer 18 is mounted close beside and parallel to the tank.

Gas is supplied from the tank 16 to the hammer 18 through well-known commercially manufactured connections comprising a supply valve 32 which is fixed on the discharge end of the tank 16, a reducing valve 34, which is to be adjusted in accordance with the requirements of the particular hammer used, and pipes 36 and 38 which connect the reducing valve with the supply valve 32 and the hammer 18, respectively.

The stem 40 of the supply valve 32 is normally urged outwardly into its closed position by the internal mechanism of the valve. In order to permit the unit 12 and float 10 to become stabilized in the water as shown in Fig. 4, before the operation of the hammer 18 has started, a time delay device is provided for actuating the supply valve. This device comprises a trigger 42 which is pivoted on a stud 44 and is spring-loaded by a spring 46 having a sufficient force stored therein to operate the valve stem 40 when the trigger is released. The stud 44

is mounted on an arm 48 which is fixed to the bracket 30, the arm having a flange 50 which provides an abutment for the upper end of the spring 46.

The trigger is normally held close to, but out of engagement with, the valve stem 40, by a cord 52 which is looped around the trigger and is secured to the flange 50. The cord is broken to release the trigger by a blasting cap 54 mounted on the arm 48 and connected to one end of a fuse 56. As shown in Fig. 3A the cord 52 is disposed in close proximity with blasting cap 54 whereby upon detonation of the cap, rupture of the cord is insured. The fuse is secured to the flange 50 by a cord 58 and has a lanyard 60 which when pulled operates a standard blasting fuse igniter to ignite the fuse 56. Thus, after a short interval (about 30 seconds), beginning with the pulling of the lanyard, the fuse sets off the cap 54 thereby initiating the operation of the hammer 18.

The anvil 22 is soldered to the mid-portion of the resonator tank 16 at the side thereof. Various tests made with the anvil and hammer in different positions with respect to the tank, indicate the superiority of the illustrated arrangement from the standpoints of both volume and directionality of the sound produced. As a result of investigating the directionality pattern of the illustrated sound generator, it has been found to provide a substantially constant intensity of sound in all directions with regard to a plane including the longitudinal axis of the tank as well as a plane perpendicular to the axis of the tank.

The upper end of the float is tightly closed except for the restricted orifice 26. This orifice is made to close limits by soldering a tungsten wire, .010" in diameter, into a larger hole in the tank near its upper end, and then withdrawing the wire to which the solder does not adhere. Near the lower end of the float and fixed thereto is a clip 62 to which the line 14 is attached, the other end of the line being tied around the discharge end of the resonator tank 16.

The door 24 closely fits the lower end of the float and is normally held closed by a spring hinge 64.

Exhaust holes 59 in the hammer may be sealed watertight by a piece of tape which is broken by the exhaust gases from the hammer as soon as it begins to operate. A similar temporary seal may be made between the striker 20 and the body of the hammer.

Briefly to summarize the operation of the illustrated sound generator, when occasion for its use arises, the unit 12 is removed from the float 16 and after the lanyard 60 is pulled to ignite the fuse 56, the unit and float are dropped over the side of the ship. The unit 12 quickly sinks making the line 14 taut and hence righting the float so that it stands vertically in the water as indicated in Fig. 4. At this time the unit is suspended about 25 feet below the surface of the water and begins to operate as soon as the fuse 56 sets off the cap 54.

Owing to the weight of the unit 12 the air which is trapped in the float is compressed somewhat and slowly discharges through the orifice 26. Consequently, the water rises slowly in the float throughout the period of operation of the hammer. Eventually, when the gas supply in the tank 16 is exhausted, the buoyancy of the float is diminished to the point where it will no longer support the unit 12 and then the float and unit together sink to the bottom.

What is claimed is:

1. A sound generator comprising a resonator tank adapted to hold compressed gas, an anvil fixed to said tank, a gas-operated hammer having a high striking frequency arranged to impinge on said anvil connections between said container and hammer for supplying gas to the latter, said connections comprising a valve and a pressure reducing valve, a spring loaded trigger for opening said supply valve, means for holding said trigger in an inoperative position away from said valve and explo-

sive means for releasing said last-mentioned means whereby said supply valve is opened by said trigger.

2. A sound generator comprising a resonator tank adapted to hold compressed gas, an anvil fixed to said tank, a gas-operated hammer having a high striking frequency mounted on said tank and arranged to impinge on said anvil, connections between said container and hammer comprising a supply valve and a pressure reducing valve, a spring operated trigger for operating said supply valve, means for releasably holding said trigger away from said valve, said means comprising a fuse and cap constructed and arranged to free said trigger at the end of a short interval after said fuse is ignited.

3. A sound generator comprising a resonator tank adapted to hold compressed gas, a gas operated hammer having a high striking frequency secured to said tank, an anvil fixed to said tank and arranged to be successively engaged by said hammer, connecting means between said tank and said hammer for supplying gas to the latter, a trigger mechanism operable to permit flow of gas from said tank to said hammer, and explosive means for releasing said trigger mechanism.

4. A sound generator comprising a resonator tank adapted to hold compressed gas, an anvil mounted on said tank at the mid-portion thereof, a gas operated hammer having a high striking frequency arranged to successively impinge upon said anvil, connecting means including a supply valve between said tank and said hammer for supplying gas to the latter, a spring loaded trigger for opening said supply valve, means for holding said trigger in an inoperative position away from said valve, and explosive means for releasing said last mentioned means whereby said supply valve is opened by said trigger.

5. A sound generator comprising a resonator tank adapted to hold compressed gas, an anvil mounted on said tank at the mid-portion of said tank, a gas-operated hammer having a high striking frequency arranged to impinge on said anvil, connecting means including a shut-off valve and a pressure-reducing valve between said tank and said hammer for supplying gas to the latter at the operating pressure of said hammer, a spring loaded trigger for opening said shut-off valve, means holding said trigger in its inoperative position, and explosive means for releasing said last-mentioned means after a predetermined interval from an initial time whereby said shut-off valve is opened by said trigger.

6. A sound generator comprising, in combination, a cylindrical tank adapted to hold gas under pressure, an anvil secured to said tank, a gas-operated hammer having a high striking frequency secured to said tank and arranged successively to engage said anvil, and means connecting said tank with said hammer for supplying gas to said hammer at its operating pressure.

7. A sound generator comprising, in combination, a tank adapted to hold a compressed gas, an anvil secured to the wall of said tank substantially equidistant the ends thereof, a gas-operated hammer having a high striking frequency secured to said tank in substantially parallel relationship with said tank and arranged successively to impinge on said anvil, and gas-conducting means connecting said tank with said hammer for supplying gas to said hammer at its operating pressure.

8. A sound generator comprising, in combination, a cylindrical tank adapted to hold gas under pressure, an anvil secured to said tank at the mid-portion thereof, a gas-operated hammer having a high striking frequency secured to said tank and arranged successively to impinge on said anvil, said tank functioning as a resonator of sound waves produced by the striking of said anvil by said hammer, gas-conducting means including a shut-off valve connecting said tank with said hammer, and means for opening said shut-off valve after a predetermined interval from an initial time.

9. Apparatus in accordance with claim 8 wherein said last-mentioned means comprises a spring loaded trigger

normally held away from said shut-off valve, and explosive means for releasing said trigger to open said shut-off valve.

10. Apparatus in accordance with claim 8 wherein said last-mentioned means comprises a spring loaded trigger normally held away from said shut-off valve by a cord, and a fused detonating cap positioned adjacent said cord for rupturing said cord and releasing said trigger to open said shut-off valve.

11. A sound generator comprising, a resonator tank 10 adapted to hold gas under pressure, an anvil secured to said tank at the mid-portion thereof, a gas-operated hammer secured to said tank and arranged successively to impinge on said anvil at a high frequency, gas-conducting means including a shut-off valve and a pressure re- 15

ducing valve connecting said tank with said hammer, a spring-loaded trigger for opening said shut-off valve, a cord holding said trigger in an inoperative position away from said shut-off valve, and a detonating cap having a fuse attached thereto mounted adjacent said cord for rupturing said cord at the end of a short interval after said fuse is ignited thereby permitting the flow of gas from said tank to said hammer.
